United States Patent Office

Des. 222,238

Patented Oct. 12, 1971

222,238

CRATE

Houston Rehrig, 3730 E. 26th St.,
Los Angeles, Calif. 90023

Filed Jan. 13, 1970, Ser. No. 20,903

Term of patent 14 years

Int. Cl. D9—04

U.S. Cl. D9—247

FIG 1

FIG 2

FIG. 3

FIG. 4

FIG. 1 is a front perspective view of a crate showing my new design;

FIG. 2 is a top plan view thereof;

FIG. 3 is a side elevation view thereof, the other side being identical thereto; and

FIG. 4 is an end elevation view thereof, the other end being identical thereto.

I claim:

The ornamental design for a crate, substantially as shown and described.
